Primary Examiner—James R. Largen

Attorney, Agent, or Firm—W. Scott Carson

[57] CLAIM

The ornamental design for a housing for a shut-off valve, as shown and described.

DESCRIPTION

FIG. 1 is a perspective view of a housing for a shut-off valve showing our new design.

FIG. 2 is a side elevational view thereof, the opposite side being a mirror image of the side shown.

FIG. 3 is a front elevational view thereof.

FIG. 4 is a rear elevational view thereof.

FIG. 5 is a top plan view thereof.

FIG. 6 is a bottom plan view thereof.
